ELECTRICAL NETWORK

Arthur W. Vance, Haddonfield, N. J., assignor to
 Radio Corporation of America, a corporation
 of Delaware

Application October 25, 1939, Serial No. 301,269

5 Claims. (Cl. 178—44)

This invention relates to electrical networks or circuits to be operated at high frequencies, and has for its principal object the provision of an improved apparatus and method of operation for minimizing phase shift in the output voltage of such circuits during high frequency operation.

A copending application of Nils Johann Oman, Serial No. 153,574, filed July 14, 1937, and assigned to the same assignee as the present application, discloses one important application of the improved network in connection with the feedback of energy between the input and output circuits of electron discharge amplifiers. In the illustrated embodiment of the present application, as in that of the copending application, the improved network functions as the coupling between the last stages of an audio frequency amplifier and involves the provision of phase correcting elements which serve to bypass the leakage reactance of the coupling at high frequency.

The invention will be better understood from the following description considered in connection with the accompanying drawing, and its scope is indicated by the appended claims.

Figures 1 and 2 are explanatory diagrams relating to the operating characteristics of the invention,

Figure 3 is a wiring and block diagram illustrating a preferred embodiment of the invention, and

Figures 4 and 5 illustrate different modifications of a detail of the circuit of Fig. 1.

It is well known that transformers introduce large phase shifts at high frequencies, due to the action of the primary and secondary capacities and the leakage inductance between primary and secondary. Thus, 360° lag is approached at very high frequencies between the primary input current and the secondary voltage. If the leakage reactance could be shorted out, the maximum would become 90° lag. In transformers of ratios near unity, a condenser may be connected between primary and secondary points of like voltage and polarity and so short-out the leakage reactance between these points (for high frequencies) and greatly improve the phase and attenuation characteristics.

The approximate equivalent diagram of a transformer energized through a vacuum tube at high frequencies is shown in Fig. 1. This is seen to be similar to a low pass filter driven from a resistance generator. At high frequency, the filter itself approaches 180° lag in phase while, since its impedance becomes capacitive, the voltage across the input to the filter (across capaci-

tor 10) is seen to approach 90° lag. Thus, 360° total lag is approached and, of course, the attenuation becomes very great. This condition is very undesirable in feedback circuits where phase delays of 180° in the whole feedback loop must be avoided if stability is to be obtained. If a condenser 11 is shunted across the reactor 12, as is shown by dotted lines, then at very high frequencies the diagram becomes equivalent to that 10 of Fig. 2.

This is simply a capacity divider driven through a resistance and the maximum phase delay is 90° lag. Since capacitor 11 shunts inductance 12 and resistor 14 in Fig. 1, a parallel 15 tuned circuit is formed in series between the input and output at some frequency. If 11 and 14 are made large compared to 12, the maximum impedance reached by their tuned circuit may be made negligible. If necessary, an additional 20 resistance may be inserted in series with 11 to limit the tuned impedance, but this will permit the circuit to go to 180° lag at infinite frequency instead of 90°. However, in practice, the resistance used may be made so small as to have negligible effect at any desired frequency.

A stepup transformer with one side common to the primary and secondary windings reduces at high frequencies to the equivalent of an auto-transformer with two parallel-connected primary 30 windings. For ratios near unity, the leakage inductance of an auto-transformer is much less than that of the equivalent transformer. For instance, for 2/1 ratio, the leakage of the auto-transformer is one-fourth that of the transformer. Such a stepup transformer is interposed between the last two stages of the audio frequency channel illustrated by Fig. 3.

The channel of Fig. 3 includes an input transformer provided with a primary winding 15 and 40 a secondary winding 16 which is shunted by a loading resistor 17 and capacitor 18 and connected in the input circuit of an amplifier 19. The output circuit of the amplifier 19 is coupled through successive stages 20 and 21 and a stepup 45 transformer 22 to the input circuit of the last amplifier stage 23. The output circuit of the amplifier 23 is coupled to a load circuit 24 through a transformer 25.

It will be noted that the transformer 22 includes a primary winding 26 and a secondary 27, that substantially equipotential points of these windings are interconnected through a capacitor 28, and that a capacitor 29 is connected across the section 30 of the winding 27 or between the

equal voltage point and the high voltage terminal of the secondary winding.

As previously indicated, such a transformer operated at high frequencies is the equivalent of an auto-transformer which exhibits a leakage reactance much lower than that of the usual two-winding transformer. If the winding section 30 is sandwiched between the windings 26 and 27, a great additional reduction in leakage inductance is realized. If the section 30 is shunted by the capacitor 29 as illustrated, this winding section is substantially bypassed at high frequencies and the phase lag of the voltage applied to the input circuit of the stage 23 cannot exceed 90°.

Resonance effects in this type of network may be controlled by connecting across the winding section 30 various combinations of reactance and resistance such as (1) that illustrated by Fig. 4, in which the capacitors 31 to 33 and the resistors 35 and 36 become progressively smaller from left to right, or (2) that illustrated by Fig. 5, in which the capacitors 37 to 40 and the resistors 41 to 43 are similarly arranged. Such arrangements, of course, tend to reduce the negligible impedance at infinite frequency and to damp-out resonance with the inductances which they shunt.

Between the output circuit of the stage 23 and the input circuit of the stage 19 is provided a degenerative feedback circuit which includes a plurality of capacity-resistance voltage divider units 44 to 49, the last of these units being included in the input circuit of the stage 19. This specific feedback circuit forms no essential part of the present invention and is described in greater detail in the aforesaid copending application.

I claim as my invention:

1. An electrical network including a transformer provided with primary and secondary windings having a transformation ratio other than unity, capacitance means connected between equal voltage points of said windings for shunting their leakage reactance at high frequencies, said secondary winding having a high voltage section, and capacity means providing a high frequency path in shunt with said section of the secondary, whereby said section is substantially bypassed at high frequencies and the phase lag

of output voltage from the network is less than ninety degrees.

2. In an audio frequency amplifier, an inter-stage coupling network including an audio frequency stepup transformer provided with primary and secondary windings, means providing a high audio frequency path of relatively low impedance between substantially equal voltage points of said windings, and means providing a high audio frequency path in shunt relation to a high voltage section of said secondary winding between the terminal of said first named path on said winding and a terminal of the network.

3. In an electric wave transmission system, a signal circuit coupling network, a stepup coupling transformer included in said network, means affording a high frequency path between substantially equal voltage points of the primary and secondary windings of said transformer, and means affording a high frequency path in shunt to a high voltage section of said secondary winding having an impedance value for minimizing phase shift in the secondary voltage of said transformer at high frequencies.

4. An audio frequency coupling circuit including a transformer having a ratio of transformation other than unity, means providing a high audio frequency signal conveying path between the high potential end of the lower impedance winding of the transformer and a tap on the higher impedance winding thereof providing substantially unity transformation ratio, and means providing a second high audio frequency path between said tap and the high potential side of said circuit.

5. An audio frequency coupling circuit including a transformer having lower and higher impedance windings providing a ratio of transformation other than unity, means providing a high audio frequency signal conveying connection between the high potential end of the lower impedance winding and a tap on the higher impedance winding providing substantially unity transformation ratio, and means providing a second high audio frequency signal conveying connection between said tap and the high potential side of the circuit to which the higher impedance winding is connected.

ARTHUR W. VANCE.
